UNITED STATES PATENT OFFICE.

JAMES H. KELLY AND EDWARD P. FOLLETT, OF ROCHESTER, NEW YORK;
SAID FOLLETT ASSIGNOR TO SAID KELLY.

LANTERN.

SPECIFICATION forming part of Letters Patent No. 369,010, dated August 30, 1887.

Application filed August 25, 1886. Serial No. 211,793. (No model.)

To all whom it may concern:

Be it known that we, JAMES H. KELLY and EDWARD P. FOLLETT, both citizens of the United States, residing at Rochester, in the county of Monroe and State of New York, have invented a certain new and useful Improvement 5 in Lanterns; and we do hereby declare that the following is a full, clear, and exact description of the same, reference being had to the drawings accompanying this application.

Our improvement relates to that class of lanterns known as "tubular," and is of that kind where the cap that holds the top of the globe is capable of being moved vertically for the purpose 15 of releasing the top of the globe or raising it to light the burner.

The invention consists in the construction, combination, and arrangement of parts, hereinafter more fully described, and definitely 20 claimed.

In the drawings, Figure 1 is a front elevation of a lantern provided with our improvement. Fig. 2 is an elevation, partially in section, of the lower portion thereof in line xx of Fig. 1, the full lines showing the lantern closed and the dotted lines showing it thrown over to one side on its hinge, thereby exposing the burner for lighting. Fig. 3 is an enlarged longitudinal section through the top thimble and 25 sliding tube. Fig. 4 is a perspective view of the upper end of the sliding tube. Fig. 5 is a cross-section in line yy of Fig. 3. Figs. 6 and 7 are elevations of the lantern and top cap, respectively, showing a modification.

In the drawings, A indicates the oil pot or 30 fount; B, the air-chamber; C C, the side tubes; D, the globe-holding disk; E, the globe or chimney; G, the cap at the top of the lantern, and H the bail or handle. The air-chamber B is 35 made of two parts, a b , hinged together at c , and provided with any suitable catch or locking device, d , by which means the upper portion of the lantern can be turned over, as indicated by the dotted lines in Fig. 2. The side 40 tubes are attached to the upper part, b , and the cone also is attached to or made solid with it. Therefore, when the upper portion of the lantern is turned back, as indicated by dotted lines, Fig. 2, the portion b of the air-chamber 45 and all above and connected with it move together, and the cone is thereby removed from

over the wick, (as the wick-tube rests in the oil port or base A,) thus allowing the wick to be lighted, trimmed, or extinguished without difficulty.

55

Our improvement is as follows:

J is an open-ended thimble at the top of the lantern, with which the side tubes, C C, connect, said side tubes opening through the thimble.

I is a tube resting closely but sliding freely 60 in the thimble, and having the cap G attached to its lower end. The top of the tube is closed, but the bottom open to admit the draft. In two opposite sides of the tube are made slots of Z form, consisting of a vertical slot, f , and 65 two horizontal connecting-slots, $f'f''$, which extend in opposite directions, as shown in Fig. 4.

g is a pin extending through the thimble and resting in the slots of the tube on opposite sides.

Instead of the pin described, one or more 70 studs may be used, attached to the thimble and projecting inward and resting in the slot or slots.

h are two openings made in the sides of the sliding tube. When the tube is forced 75 down to its lowest position to hold the top of the globe, these openings h coincide with the open ends of the tubes and openings in the thimble, and thus allow the draft to pass into the tubes, as exhibited by 80 the arrows in Fig. 3. The tube is raised or lowered by turning it so that the stud or pin passes into the vertical slot, and it is held either raised or lowered by turning it to the right or left, so that the stud or pin passes into 85 one or the other of the horizontal slots. By this means, when turned down, the fastening rests closely on top of the globe and holds it in place, and when turned up it is held elevated either to release the globe and allow it 90 to be taken out or to hold the globe up, as will be hereinafter described.

The advantage of this arrangement is that a simple open-ended thimble and a tube sliding therein serve as the adjusting devices at the 95 top of the lantern, enabling the top to be raised and lowered, and at the same time providing means by which the draft from the interior of the globe to the side tubes is maintained. This is accomplished by the openings h , which coincide with the openings of the side tubes when lowered. By this means air-chambers at the 100

top are not required and the air is simply passed through the sliding tube.

When the lantern is constructed as shown in Fig. 1, the top is raised only to insert or remove the globe. The burner is lighted by simply turning the top of the lantern on the hinge, as before described. In some kinds of lanterns it may be desirable to raise the globe, in which case the construction shown in Figs. 6 and 7 may be used. In that case stays *k k* connect the cap G with the disk D, so that when the cap is raised the disk, and with it the globe, will be raised at the same time. To enable the globe to be removed the cap is provided with the ordinary spring wire or clamp, K, or other equivalent fastening device.

Having described our invention, we do not broadly claim slots in a lantern-cap, as the same have before been used.

20 What we claim as new is—

1. The combination, with a tubular lantern, of the open-ended thimble, to which the side tubes are attached, and the sliding tube resting therein, said sliding tube being provided 25 with openings that register with the openings of the side tubes when the sliding tube is lowered, as set forth.

2. The combination, with a tubular lantern, of the open-ended thimble, to which the side 30 tubes are attached, and the sliding tube rest-

ing therein, said sliding tube being provided with a slot or slots in which rests a stud or pin of the thimble, and provided with openings that register with the openings of the side tubes when the sliding tube is lowered, substantially as and for the purpose specified. 35

3. In a tubular lantern, the combination of the air-chamber at the base of the lantern, the globe, the side tubes connecting with the air-chamber, the open-ended thimble at the top of 40 the side tubes, and the sliding tube resting in the thimble, said sliding tube being provided with a slot or slots and openings, in the manner and for the purpose specified.

4. In combination with a tubular lantern, 45 an open-ended thimble, to which the side tubes are attached, a sliding tube resting in said thimble, provided with openings that register with openings in the side tubes, and stay-wires connected with the sliding tube, said stay-wires 50 supporting the chimney, as and for the purpose specified.

In witness whereof we have hereunto signed our names in the presence of two subscribing witnesses.

JAMES H. KELLY.
EDWARD P. FOLLETT.
